UNITED STATES PATENT OFFICE.

CHARLES A. LAMMERS, OF STILLWATER, MINNESOTA.

COPY-HOLDER.

1,087,304.

Specification of Letters Patent.

Patented Feb. 17, 1914.

Application filed August 4, 1910. Serial No. 575,427.

To all whom it may concern:

Be it known that I, CHARLES A. LAMMERS, a citizen of the United States, residing at Stillwater, in the county of Washington and 5 State of Minnesota, have invented certain new and useful Improvements in Copy-Holders, of which the following is a specification.

My invention relates to improvements in 10 copy holders for book typewriters and billing machines, its object being particularly to provide copy holders which may be removably supported on the stationary framework of the machine without interfering 15 with the movable writing mechanism.

To this end my invention consists in the 20 features of construction, combination and arrangement of parts hereinafter particularly described and claimed.

25 In the accompanying drawings forming part of this specification, Figure 1 is a perspective view of my improved invention shown in use; Fig. 2 is a side elevation of the same removed; and Fig. 3 is a front view partly broken away.

Referring to the drawings A represents conventionally a book typewriter and billing machine of the usual construction having 30 transversely traveling mechanism 2, fixed side bars 3 being carried by the framework.

My improved copy holder comprises a 35 spring sheet metal bar or frame B having hooked ends 4 to fit over the side bars 3 of the machine framework. The horizontal cross bar 5 of the copy holder frame is preferably upwardly bowed as shown in Fig. 3 and the arm 6 inwardly bent to allow the holder to be supported by spring pressure upon the bars 3. Secured upon the cross 40 bar 5 are the spring brackets 7 having notches 8 to receive the shaft ends 9 of the roller 10. The upwardly bent spring ends 11 of the brackets form journal supports for the idler roller 12. A spring strip 13 is 45 connected with the upwardly bent end 14 of one bracket and fits under a catch 15 car-

ried by the corresponding end of the other bracket, as indicated in Fig. 1.

In use the copy holder is supported on the machine by having its free ends sprung over 50 the cross bar 3. The spring strip 13 may be turned into dotted line position shown in Fig. 1 to allow the copy to be inserted between the rollers and the strip carried under the catch 15 to hold the copy paper in position. The strip 13 has pivot connection 16 with the upwardly bent end 14 of one of the brackets 7. The upwardly and rearwardly bent end 15 of the other bracket forms a catch under which the free end of the strip 60 is held when turned into the position shown in Fig. 1.

I claim among the advantages of my machine, the simplicity of construction, and the ease of supporting it from the fixed framework of the machine without interfering with the movable writing mechanism, and 65 in the most convenient position for use.

I claim as my invention:

In combination with a resilient element 70 comprising a horizontal portion, downwardly extending side arms constructed for spring support upon the sides of the machine, a copy holding roller mounted upon the horizontal portion of said element, bearing members for said roller mounted upon said element, curved terminals upon said bearings and an idler roller journaled in said terminals and bearing against the first named roller, upturned terminals upon the 75 said bearing members at the opposite end thereof, a spring strip pivotally connected to one of said upturned terminals, and a latch carried by the other of said terminals for engagement with said strip. 85

In testimony whereof I affix my signature in the presence of two witnesses.

CHARLES A. LAMMERS.

Witnesses:

H. S. JOHNSON,
H. SMITH.
